US0D1035986S

(12) United States Design Patent (10) Patent No.: US D1,035,986 S
(45) Date of Patent: * Jul. 16, 2024

(54) LIGHTING FIXTURE

(71) Applicant: Kohler Co., Kohler, WI (US)

(72) Inventors: Erin Leigh Hoover, New York, NY (US); Nicholas Robert Rindt, Grafton, WI (US); Dennis Lee Snyder, Avon Lake, OH (US); Seth M. Stevens, Los Angeles, CA (US); Maxwell Wasscher, Grafton, WI (US); Luke James Worth, Sheboygan, WI (US); Jovello Tijano Gomez, Jr., Sheboygan, WI (US)

(73) Assignee: Kohler Co., Kohler, WI (US)

() Term: 15 Years

(21) Appl. No.: 29/886,880

(22) Filed: Mar. 14, 2023

(57) CLAIM

The ornamental design for a lighting fixture, as shown and described.

DESCRIPTION

FIG. 1 is a perspective view of the claimed design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines shown in the drawings depict portions of the lighting fixture that form no part of the claimed design.

1 Claim, 7 Drawing Sheets
